Primary Examiner — T. Chase Nelson*Assistant Examiner* — Michelle E Wilson(74) Attorney, Agent, or Firm — Andres E. Velarde; Brian M. Bolam(57) CLAIM

The ornamental design for a sanitary towel, as shown and described.

DESCRIPTION

FIG. 1 is a top view of one embodiment of a sanitary towel; and,

FIG. 2 is a perspective view of the embodiment of FIG. 1. The broken lines shown in the drawings are for illustrative purposes only; they indicate the boundaries of the claimed design and form no part of the claimed design.
